ABSTRACT

Selective transfer circuit using transistors and diodes. A time variable gating signal is applied to a coincidence gating chain to trigger a selected transistor into conduction thereby activating an output device individual to the activated transistor. Isolating diodes are used to prevent cross activation of transistors.

SELECTION CIRCUIT

The present invention relates to a selection circuit including a plurality of selection indicating devices, preference means to selectively establish a preference order of operation of said devices and operating means to effectively operate the first device of said established order, said preference means being constituted by a closed loop of series connected elements which are each coupled to a distinct one of said devices and by means to selectively connect a bias source to a junction point of said series connected elements.

Such a selection circuit is already known from Belgian Pat. No. 647 018 (A. Henquet et al. 53-1-1). In this known selection circuit said devices are constituted by relays each with an operate winding and with a hold winding. This hold winding is connected to a distinct one of said elements which are each constituted by a change-over contact of the associated relay and more particularly to the make contact of this change-over contact. Due to the fact that the above devices are constituted by relays which operate relatively slowly and also due to their contacts operating relatively slowly a relay is only effectively operated, i.e., maintained in operative condition through its hold winding, after a considerable time has elapsed. Subsidiarily, no means are provided to prevent the temporary operation of a relay via its operate winding since said preference means only control the holding of the relays and not the initial operation thereof.

It is therefore an object of the present invention to provide a selection circuit of the above type, but which does not present the above drawbacks.

The selection circuit according to the present invention is particularly characterized in that said elements are constituted by unidirectional second bias sources the junction points of which are each coupled to a distinct one of said devices.

The present selection circuit is also characterized in that each of said devices is constituted by a coincidence gating circuit with a first and a second input, the first and second inputs of the gating circuits being coupled to said operating means and to said junction points respectively, that said operating means are adapted to apply a time variable operating signal to said first inputs tending to activate said gating circuits and includes at least one capacitor charge circuit at the output of which said time variable operating signal is generated.

In this way the output of a gating circuit the second input of which is given preference is activated when the time variable signal applied to its first input reaches a predetermined threshold value.

It should be noted that Belgian Pat. No. 579 685 (F. Clemens et al. 2-1) already discloses the use of a time variable signal obtained with the help of a capacitor charging circuit but this signal is used as an inhibiting signal and not as a gating signal. Moreover, this circuit is a common one which is switched to inhibit some devices so that it is not effective if none of the remaining devices is driven.

In accordance with a preferred embodiment of the invention, the present selection circuit includes a plurality of capacitor charge circuits which are each connected to the base of a respective transistor, the emitters of these transistors being connected to distinct one of the junction points of a number of diode rectifiers which are connected in a closed loop and a ring counter being adapted to cyclically apply a bias potential to these junction points. The collector of each transistor is connected to the winding of a relay and to the bases of each of the other transistors via another diode rectifier so that an operated transistor prevents the operation of all the other ones.

According to a further aspect of the invention the present selection circuit which includes a plurality of selection indicating devices and operating means to effectively operate a single one of said devices, is characterized in that each of said devices is constituted by a coincidence gating circuit with a first input and a second input, the first inputs being connected to a common bias source and the second inputs being each connected to a said operating means adapted to apply to this

input a time variable signal tending to activate the corresponding gating circuit, and that the output of each one of said gating circuits is connected to the second input of each of the other gating circuits via a diode rectifier so as to prevent said other gating circuits from becoming activated when said one gating circuit is activated.

The above mentioned and other objects and features of the invention will become more apparent and the invention itself will be best understood by referring to the following description of an embodiment taken in conjunction with the accompanying drawings in which:

FIG. 1 is a schematic view of a part of an automatic telecommunication switching system including selection circuits LASM11 and LASM12 according to the invention;

FIG. 2 shows the selection circuit LASM11 in detail.

In the copending Dutch patent application dated Dec. 12, 1969, entitled "Automatic telecommunication switching system" (H. Verhille-O. Konkers 8-1) an automatic telecommunication system including eight identical switching network parts P1 to P8 is described.

Principally referring to FIG. 1, the switching network part P1 shown therein includes six crossbar switches CS1 to CS6 each with seven vertical operate bars V11 - V17 to V61 - V67 respectively and with 28 horizontal select bars H11 - H128 to H61 - H628. The crosspoints of the 22 x 6 rows which are each controlled by a respective one of the 22 x 6 horizontal select bars H11-H122 of the crossbar switches CS1 to CS6 are multiplied per row and give access to the incoming junctions

IJ11-IJ122 to IJ61-IJ622 respectively. The crosspoints of the 6 x 6 remaining rows which are each controlled by a respective one of the 6 x 6 horizontal select bars H123-H128 of these crossbar switches CS1 to CS8 are not multiplied per row, but the homologous ones of these crosspoints are multiplied.

Each group of six thus multiplied homologous crosspoints has access to a same register among 42 registers RE1 to RE42. For instance the first crosspoints of the crossbar switches CS1 to CS6, controlled by the horizontal select bars H123 to H126, are multiplied and give access to register RE1. Switching network part P1 further includes six switch control circuits, hereinafter called link access circuits LAC1 to LAC6, each associated to a respective one of the switches CS1 to CS6.

From the above it follows that all the incoming junctors have access to all the registers RE1 to RE42. More particularly these incoming junctors have access to the seven groups of registers RE1-RE6, . . . , RE37-RE42 each time under the control of a respective one of the seven vertical bars forming part of the switch to which these incoming junctors are connected.

The above switching network part P1 is controlled by two markers M11 and M12 which include each a link access selection matrix LASM11 and LASM12 respectively.

In brief the above circuitry which is described in detail in the above mentioned patent application operates as follows. When one or more of the incoming junctors IJ11-IJ628 calls or call for being connected to one of the registers RE1 to RE42, this call or these calls is or are transmitted to and registered by a call registering relay Ear (not shown) in the link access circuit LAC1-LAC6 associated to the crossbar switch CS1-CS6 to which the calling incoming junctor is connected.

This registration is however only performed on condition that at least one of the vertical operate bars V11-V17 to V61-V67 of this switch and at least one of the registers coupled to a crosspoint controlled by this vertical bar is available.

Each of the six link access circuits LAC1 to LAC6 which has thus registered a call from at least one of the incoming junctors connected to the respective crossbar switch CS1-CS6 calls for the intervention of one of the two markers M11 and M12 by applying a calling battery simultaneously to the link access matrices LASM11 and LASM12 included in these markers. Hereby it should be noted that a link access circuit is only able to apply a calling battery to a link access matrix when the start relay Str (not shown) included in this circuit is in the released condition, and that a link access matrix is

available only when all the relays included in the corresponding marker are also in the released condition. Each available link access matrix then selects one of the six possible calling link access circuits LAC1-LAC6 according to a predetermined priority. For instance, the LASM11 included in the marker M11 selects the calling LAC1 associated to the crossbar switch CS1 by operating relay L1r which is associated to the LAC1 in the LASM11. Following the operation of the relay L1r the relays Mgr (FIG. 2) and M1r (not shown) are operated. These relays hereby block the LASM11 against calls from one of the other link access circuits LAC2 to LAC6. The marker M11 then selects a calling incoming junctor, e.g., IJ11, connected to a crosspoint of crossbar switch CS1 to which the selected LAC1 is associated and operates the horizontal select bar H11 controlling this crosspoint. Consequently the above start relay Str is then energized in the LAC1 to prevent this circuit from making a renewed call although other incoming junctors IJ12-IJ122 connected to the CS1 may be in the calling condition. The operation of relay Str is followed by the release of relay L1r due to which the relays Mgr and M1r now block the LASM11 against calls from all the link access circuits LAC1 to LAC6. A connection is then established between the selected calling incoming junctor IJ11 and a free register, e.g., RE1, by the subsequent operation of the horizontal select bar H123 and the vertical bar V11. Afterwards the relays Str, Mgr and M1r are released in succession, the LASM11 and the marker M11 being again available when relay M1r is in the released condition.

Principally referring to FIG. 2, the link access selection matrix LASM11 shown therein includes six capacitor charge circuits part of which is located in a respective one of the link access circuits LAC1-LAC6 and which are each constituted by the series connection of a ground in the LASM1, a parallel circuit R11, C11-R16, C16, a Zener diode Z11-Z16, a column conductor CW1-CW6, a terminal V1-V6, a resistance R21-R26, a terminal X1-X6 connected to the LAC1-LAC6, a break contact st (LAC1) - st (LAC6) of the start relay Str included in the LAC1-LAC6, a make contact ea (LAC1) - ea (LAC6) of the call registering relay Ear included in the LAC1-LAC6, a resistance R31-R36 and a battery.

The junction points I1 to I6 of each parallel circuit R11, C11-R16, C16 and the respective Zener diode Z11-Z16 is connected to the base electrode of a respective PNP transistor T1-T6. The emitter electrodes of these transistors T1-T6 are each connected to a respective one of the junction points J1 to J6 of the six diode rectifiers D11 to D16 which are series connected in a closed loop. A step-by-step switch S is adapted to cyclically apply a bias ground to terminals P1 to P6 and hence to the junction points J1 to J6. Obviously any other type of ring counter could be used instead of switch S.

The collector electrodes of the transistors T1 to T6 are connected to the tapping point T of a common potentiometer R4, R5 via the series connection of a respective conductor C1-C6, a respective terminal Y-Y6, and the winding of a respective relay L1r-L6r. The collector electrodes of the transistors T1 to T6 are further each connected to a respective one of the row wires rw1 to rw6 of a diode matrix DM via a respective diode rectifier D21 to D26. These row wires rw1 to rw6 are themselves each connected to five column wires cw2-cw6 to cw1-cw5 each time via an individual diode rectifier. For instance the row wires rw1 and rw6 of the DM are connected to the column wires cw2-cw6 and cw1-cw5 respectively via diode rectifiers D'12-D'16 and D'16-D'65 respectively.

The above relays L1r-L6r each have a make contact /11-61, which is adapted to connect a ground to a respective one of the terminals Z1-Z6 leading to the row wires rw1-rw6 respectively, the diode rectifiers D41-D46 being not always necessary.

The above described circuitry is the basic one but additional circuitry may be added to it.

For security reasons, as will be explained later, a ground is connected to the above junction points J1-J6 via a common Zener diode Z21 and a respective diode rectifier D31-D36.

The make contacts /11-16 may be connected to the winding of a control relay Mgr in which case the decoupling rectifiers D41-D46 and D51-D56 must be provided. The make contact mg1 of this relay Mgr is used to connect a common ground to the terminals U1-U6 of the respective column wires cw1-cw6 via a respective break contact 112-162 of the relay L14-L6r and a respective diode rectifier D61-D66. The make contact mg1 is shunted by contact ml of the above mentioned relay mbr (not shown).

10 The matrix DM may also include an inhibiting row conductor rw7 which is connected to each of the terminals V1 to V6 on the column conductors cw1 to cw6 via a respective diode rectifier D81-D86 and the terminal P. The latter terminal P is connected to ground via a break contact am of control relay Amr (not shown) and a diode rectifier D7 in series.

15 Finally the terminal W1-W6 of each of the row conductors rw1-rw6 of the LASM11 may be connected in the LASM12 to the junction point V1-V6 of a column conductor cw1-cw6 and a resistance R21-R26 via a decoupling diode rectifier D91-D96 and a terminal Q1-Q6.

20 The operation of the above described selection matrix LASM11 without considering the inhibiting row conductor rw7 as follows.

25 It is supposed that at the moment the marker M11 becomes available due to its relay mbr being released all the contacts of the LAC1-LAC6 and of the marker M11 are in the position shown, except for the contacts ea (LAC1) and ea (LAC6) which are supposed to be in their operated condition due to 30 the corresponding relays Ear (LAC1) and Ear (LAC6) being in their operated condition. The operated relays Ear in the LAC1 and in the LAC6 indicate that one of the incoming junctors connected to the CS1 and to the CS6 respectively call for a register.

35 Due to contacts ea (LAC1) and ea (LAC6) being closed the capacitors C11 and C16 simultaneously start charging between ground and battery in the following respective circuits:

40 R11, C11, Z11, cw1, R21, X1, st (LAC1), ea (LAC1) and R31;
R16, C16, Z16, cw6, R26, X6, st (LAC6), ea (LAC6) and R36.

45 Consequently the potential at the base electrodes I1 and I6 of the transistors T1 and T6 gradually decreases towards battery. Since the emitter of transistor T1 is directly connected to the ground provided by the switch S, whereas the emitter of transistor T6 is connected to the same ground via the series connection of five diode rectifiers D11 to D15 each producing a voltage drop of v Volts, it is clear that transistor T1 will be rendered conductive before transistor T6. As soon as the transistor T1 is rendered conductive the ground connected to its emitter is applied via its emitter-to-collector junction to conductor c1 and from there

55 on the one hand to the column conductors cw2 (not shown) to cw6 via the common diode rectifier D21, the row wire rw1, and the individual diode rectifiers D'12 to D'16 respectively. Due to this none of the capacitors C12 to C16 can be charged to a potential sufficient to render conductive the associated transistor T2 to T6. In other words an electronic exclusion of the transistors T2 to T6 is realized. Hereby it should be noted that an electronic exclusion is already known from the above mentioned Belgian Pat. No. 579 685 (F. Clemens et al. 2-1);
60 on the other hand to the one end of the winding of relay L1r, the other end of this winding being connected to the tapping point T of the potentiometer R4, R5. The transistor T1 and the relay L1r are hence operated in series.

65 70 The energized relay L1r which indicates that the LAC1 is selected closes its contact /11 due to which a further ground is connected to the row wire rw1 via diode rectifier D41 and hence to the column conductors cw2 (not shown) to cw6 via the diode rectifiers D'12 to D'16 respectively. The transistors T2 to T6 and the associated relays L2r to L6r are hence

further prevented from being operated. In other words by the closure of contact *l11* an electromechanical exclusion of the transistors *T2-T6* is realized. By preventing the transistors *T2* to *T6* from being operated it is clear that the *LASM11* is blocked against calls from the link access circuits *LAC2-LAC6*, this blocking being under the control of *T1* and *L1r*.

In the above example the column conductors *cw2* to *cw6* are each connected to ground via three diode rectifiers subsequent to the operation of transistor *T1*, i.e., the emitter-to-collector junction of this transistor, *D21* and *D'12-D'16* since the emitter of this transistor *T1* is directly grounded due to the switch *S* being in the first position *P1* shown. When the switch *S* is, however, for instance in the second position *P2*, it is clear that this ground will be applied to the emitter of transistor *T1* via the five diode rectifiers *D12* to *D16* so that the ground potential is then applied to the column conductors *cw2-cw6* via eight diode rectifiers, i.e., *D12* to *D16*, *T1*, *D21* and *D'12-D'16* at the moment the transistor *T1* is rendered conductive. Since each diode rectifier produces a voltage drop of *v* Volts, e.g., 0.3 Volts, it is clear that even after the above electronic exclusion has been realized the capacitors *C12* to *C26* are able to charge between -8 v Volts and ground. This is obviously undesirable. Due to the closure of contact *l11* such charging of the capacitors *C12* to *C16* is, however, prevented or these capacitors are substantially completely discharged since this contact applies a ground to each of the column conductors *cw1-cw6* via two series connected diode rectifiers *D41* and *D'12-D'16* only. This is the reason why the contacts *l11* to *l61* have been provided.

The energized relay *L1r* also opens its break contact *l12* due to which terminal *U1* is disconnected from contact *mg1*.

By the closure of contact *l11* relay *Mgr* is energized via diode rectifier *D51* and its first winding. It is locked in a not shown circuit including its second winding. By the subsequent closure of contact *mg1* a locking ground is applied to the terminals *U2* (not shown) to *U6* via this common contact *mg1*, a respective contact *l22* (not shown) -162 and a respective diode rectifier *D61-D62* so that the operation of the transistors *T2* (not shown) to *T6* is inhibited independently from the condition of transistor *T1* and hence of relay *L1r*. This means that even when transistor *T1* is blocked and relay *L1r* is released the transistors *T2* to *T6* cannot be operated as long as relay *Mgr* is operated, and that the *LASM11* is then hence blocked against calls from the link access circuits *LAC2* to *LAC6*. The operation of relay *Mgr* is followed by that of relay *Mlr* (not shown) which closes its make contact *ml* shunting contact *mg1* and thus also blocking the *LASM11* against calls from the link access circuits *LAC2* to *LAC6* in a manner independent from relay *L1r*.

As already described above the marker *M11* of which the *LASM11* forms part then selects a calling incoming junctor connected to a crosspoint of crossbar switch *CS1* and operates the horizontal bar controlling this crosspoint. Consequently the start relay *Str* of the *LAC1* is then energized. By the opening of break contact *st* (*LAC1*) transistor *T1* is cut-off and relay *L1r* is released so that the above locking ground is now also applied to the terminal *U1* via contacts *mg1* and *ml* in parallel, contact *l12* and diode rectifier *D61*. The *LASM11* is hence blocked against calls from all the link access circuits *LAC1* to *LAC6*.

A connection is then established between the selected incoming junctor and a free register and afterwards the relays *Str*, *Mgr* and *Mlr* are released in succession, the marker *M11* and hence the *LASM11* being again available when the relay *Mlr* is in the released condition. It should be noted that after the release of relay *Mgr* the switch *S* is stepped to its next position.

It should be noted that as soon as the row conductor *rw1* has been grounded due to transistor *T1* having been operated this ground is also applied to the line access selection matrix *LASM12* of the marker *M12*. Indeed, the terminal *Q1* of this row conductor *rw1* is connected to the terminal *V1* of the con-

ductor *c1* of the *LASM12* so that the transistor *T1* included therein is also prevented from being operated. This is done in order to prevent that both selection circuits *LASM11* and *LASM12* would select the same link access circuit *LAC1*.

- 5 If in the above described example the switch *S* is positioned on any of the terminals *P2* to *P6* it is clear that the transistor *T6* is made conductive before transistor *T1* since the emitter of the transistor *T6* is then connected to ground via four, three, two, one or zero rectifiers in series, while the emitter of transistor *T1* is connected to this ground via five rectifiers in series. In other words the transistor which is closest to the ground connected to one of the terminals *P1* to *P6* when considered from the grounded point towards *P6* is made conductive. Obviously this is only true when the corresponding contact *ea* is closed.
- 10 The Zener diodes *Z11* to *Z16* have been provided for the following reason. When for instance the switch *S* is in the position shown and transistor *T6* has been made conductive the ground of switch *S* is applied to the bases of the transistors *T1* to *T5* via eight diode rectifiers in series, i.e., the five diodes *D11* to *D15*, the emitter-to-collector junction of transistor *T6* and the diodes *D26* and *D'61-D'65* so that the negative potential applied to these bases is substantially equal to *V*=8v Volts, *v* being the potential drop produced across each diode.
- 15 If before the relay *L6r* has closed its contact *l61* contact *ea* (*LAC1*) is now closed, the capacitor *C11* starts charging between ground and *V*. Without the Zener diode *Z11*, it may hence happen that also the transistor *T1* is rendered conductive since the emitter thereof is directly connected to ground.
- 20 By connecting a Zener diode *Z11* in the last mentioned charge circuit in such a manner that it presents a high resistance and by choosing the Zener voltage higher than *V* the above conflicting situation cannot occur.
- 25 As already mentioned above, the circuit constituted by the diodes *Z21* and *D31* to *D36* has been chosen for security reasons. It may indeed happen that for one or the other reason the switch *S* or the equivalent counter does not connect a ground to one of the terminals *P1* to *P6*. It is clear that in this case and without precautions the circuit cannot operate. However, by providing a Zener diode *Z21* and the diodes *D31* to *D36* a voltage of about -3 Volts then appears at the junction points *J1* to *J6* when choosing a Zener diode *Z21* with a Zener voltage of about 2.7 Volts. Thus the operation of the *LASM11* is enabled. The above security circuit normally does not intervene in the operation of the selection circuit since the diodes *D31* to *D36* are normally blocked, but in case the security circuit becomes operative the above priority established by the diodes *D11* to *D16* has no effect.
- 30 It should be noted that each of the diode rectifiers *D11* to *D16* may be replaced by the series connection of a bias source and a diode rectifier, thus forming a unidirectional bias source. Also each of the transistors *T1* to *T6* could be replaced by a coincidence gating circuit.
- 35 In the above described example the selection matrix *LASM11* is normally available since the relays *Mgr* and *Mlr* are normally in the released condition. In this way, when one of the link access circuits calls for a marker the *LASM11* is able to operate immediately.
- 40 In case the above selection matrix is for instance used to select a vertical bar among a plurality of such bars and that the availability indicating batteries of these bars is applied to the selection matrix by contacts — corresponding to *ea* — of a same relay, this selection matrix oftenly selects the same vertical bars since the last mentioned contacts are substantially never closed simultaneously although they belong to a same relay. In this case it is therefore preferable to normally block the selection matrix and to unblock it only after all the above mentioned contacts have been closed. Such a circuit for normally blocking the selection matrix is constituted by the above described additional row wire *rw7* since contact *am* normally applies a locking ground to this row wire and from there to all the column wires *cw1* to *cw7*. In order to unblock the matrix *LASM11* it is sufficient to operate relay *Amr* (not shown) which then opens its contact *am*.
- 45

- 55
- 60
- 65
- 70
- 75

It should be noted that when contact arm is provided instead of the contacts /11-161, /12-162 mg1 the diodes D21-D26 may be replaced by a short-circuit.

In the above described selection circuit the operated relay L1r remains under the control of the start battery since when the latter battery is removed transistor T1 is cut-off and relay L1r is released. One may, however, also lock the relay L1r over its own contact. For instance one make contact each of the contacts /11-161 to the lower ends of the windings of the respective relays L1r-L64 in which case the diodes D21-D26 are obviously not required. Or when one provides contact arm the latter may be a change-over contact the make contact of which is connected to the lower ends of the windings of the relays L1r-L6r via a make contact of these relays.

While the principles of the invention have been described above in connection with specific apparatus, it is to be clearly understood that this description is made only by way of example and not as a limitation on the scope of the invention.

What is claimed is:

1. Selection circuit including a plurality of selection indicating devices, preference means to selectively establish a preference order of operation of said devices and operating means to effectively operate the first device of said established order, said preference means comprising a closed loop of series connected elements each coupled to a distinct one of said devices and means to selectively connect a bias source to a junction point of said series connected elements, wherein said elements comprise unidirectional second bias sources, the junction points of which are each coupled to a distinct one of said devices, each of said unidirectional second bias sources comprising a conductive rectifier, and each of said devices comprising a coincidence gating circuit with a first and a second input, the first and second inputs of the gating circuits being coupled to respective operating means and including means for generating a time variable operating signal, operating means to apply said signal to said first inputs for activating said gating circuits includes at least one capacitor charge circuit at the output of which said time variable operating signal is generated, and a plurality of said capacitor charge circuits, each coupled to the first input of a distinct one of said gating circuits, and wherein each of said capacitor charge circuits comprises a series circuit branched between a first and a second DC source and including a parallel circuit formed by a capacitor, a first resistance and a second resistance, the output of said parallel circuit being connected to a said first input of a gating circuit.

2. Selector circuit according to claim 1, wherein said bias source is constituted by said first DC source; and wherein said means to selectively connect said bias source comprise a ring counter which is adapted to cyclically connect said bias source to said junction points.

3. Selection circuit according to claim 2, further including a plurality of inhibiting means, each individually associated with a distinct one of said devices and each of which when in the operative condition prevents the effective operation of the associated device.

4. Selection circuit according to claim 3, wherein each of said capacitor charge circuits includes a make contact constituting said inhibiting means; and wherein each of said gating circuits comprises an electrical conduction device, with at least a first input electrode, a second input electrode, and an

output electrode.

5. Selection circuit according to claim 4, further including lock-out means to prevent the operation of more than one of said devices at a time.

6. Selection circuit according to claim 5, wherein the first of said lock-out means comprise a plurality of rectifiers branched between the output of each one of said gating circuits.

7. Selection circuit according to claim 6, wherein a said gating circuit is activated, a lock-out DC source is coupled to the output thereof; and said lock-out DC source comprises said first DC source.

8. Selection circuit according to claim 7, wherein the second of said lock-out means comprise a plurality of make contacts of a relay, each such contact connected to the output of a respective gating circuit, each make contact capable of connecting said lock-out DC source to the first input of each of said remaining gating circuits via a said second rectifier.

9. Selection circuit according to claim 8, wherein the output of each one of said gating circuits is decoupled from said make contact of the associated relay by a rectifier.

10. Selection circuit according to claim 9, wherein the rectifiers coupled to the first input of a same gating circuit are connected to this input via a common Zener diode.

11. Selection circuit according to claim 10, wherein each said make contact of a relay is connected, on the hand, to the winding of a second relay via an individual rectifier and, on the other hand, to a corresponding said rectifier via a rectifier and that said lock-out DC source is coupled to the first input of each said gating circuit via the series connection of a common make contact of said second relay, an individual break contact of said first relay and an individual rectifier.

12. Selection circuit according to claim 11, wherein each said last mentioned rectifier is connected to the first input of a said gating circuit via a said common Zener diode.

13. Selection circuit according to claim 12, wherein said make contact of said relay is able to connect said lock-out DC source to the output of the gating circuit to which this relay is connected.

14. Selection circuit according to claim 13, wherein a third bias source is connected to each of said junction points via a common second Zener diode and an individual rectifier.

15. A selection circuit including a plurality of selection indicating gating circuits, preference means to selectively establish a preference order of operation of said gating circuits and operating means to effectively operate the first gating circuit of said established order, said preference means comprising a closed loop of series connected elements each coupled to a distinct one of said gating circuit and means to selectively connect a bias source to a junction point of said series connected elements, wherein said elements comprise unidirectional second bias sources, the junction points of which are each coupled to a distinct one of said gating circuits, means for generating a time variable operating signal for activating said gating circuits, said generating means include at least one capacitor charge circuit at the output of which said time variable operating signal is generated, said capacitor charge circuits comprising a series circuit branched between a first and a second DC source and including a parallel circuit formed by a capacitor, a first resistance and a second resistance, the output of said parallel circuit being connected to an input of a gating circuit.

16. Selection circuit according to claim 15, wherein each of said capacitor charge circuits includes a make contact constituting said bias source; and wherein each of said gating circuits comprises an electrical conduction device, with at least a first input electrode, a second input electrode, and an
